(No Model.)

C. GEARING.

FURNACE FOR BURNING SOLID FUEL.

No. 250,064.

Patented Nov. 29, 1881.

UNITED STATES PATENT OFFICE.

CHARLES GEARING, OF PITTSBURG, PENNSYLVANIA, ASSIGNOR OF SEVEN-EIGHTHS TO SAMUEL HARPER, OF SAME PLACE, AND HENRY P. COOKE, LEWIS M. HOSEA, AND CHARLES F. HESSER, ALL OF CINCINNATI, OHIO.

FURNACE FOR BURNING SOLID FUEL.

SPECIFICATION forming part of Letters Patent No. 250,064, dated November 29, 1881.

Application filed March 26, 1881. (No model.)

To all whom it may concern:

Be it known that I, CHARLES GEARING, a citizen of the United States, residing at Pittsburg, Allegheny county, Pennsylvania, have 5 invented new and useful Improvements in Furnaces for the Combustion of Solid Fuel for Heating Purposes, of which the following is a specification.

My invention is an improvement in furnaces 10 for the combustion of solid fuels for heating purposes, and is especially applicable to iron-furnaces, steam-boilers, and other appliances used in the arts, its object being to convert the solid fuel into combustible gases by a continuous process, with a view, preferably, to the immediate combustion of the gas as fuel for the ordinary uses, and producing a high and uniform heat and a perfect utilization of the combustible matter of the coal without evolving 15 smoke, and with the maximum economy.

To this end my invention consists in the construction and arrangement of apparatus, as hereinafter more particularly described, for carrying my invention into practical operation.

25 In the accompanying drawing, illustrating one form and application of my invention, the figure is a sectional elevation of a gas-generator and its accompanying mechanism, and of a steam-boiler furnace, to which it is shown applied.

A designates the generator, and B an ordinary cylindrical return-flue boiler, to which it is applied. The generator consists, substantially, of a funnel-shaped chamber, C, with 35 walls of fire-brick or other refractory material, preferably formed, as shown, with an axis curving uniformly from the top to an approximately horizontal exit-throat, D, below, discharging into the usual combustion-chamber, E, of the boiler-furnace. At the top of the generator A is an opening, provided with a flanged casing, F, projecting upward, closed above by a hinged cover, G, and any of the common devices may be employed for feeding coal automatically through the opening, or it may be 40 fed by hand. Opening downward and through the top of the generator A, and arranged to discharge in the direction of its mean axis, is a hot-air pipe, H, connected by suitable pipes

or flues with air-heating passages arranged at 50 any convenient point in the furnace-walls for utilizing the waste-heat. I have indicated in the drawing, by dotted lines showing the general course, a passage, I, built in the side wall, and connecting the air-pipe H with air-heating 55 flues I', arranged in the floor of boiler-furnace in rear of the fire-bridge. The air is drawn through the heating-flues and driven into the generating-chamber C by means of a jet of superheated steam discharged through a small- 60 pipe, J, in the pipe H. The steam-pipe J is connected with superheating-coils, also arranged in any convenient position in the furnace or generator walls where the waste-heat may be utilized.

I have shown the coils at K, extending from side to side in a recess formed in the rear wall of the generator A, and the connecting-pipe J' may be understood to extend thence through or outside of the side wall of the generator.

A hot-air pipe or channel, L, also extends into the chamber C, near the bottom, discharging in the direction of the exit-throat D. The heated air is also supplied by suitably-disposed passages from a convenient source of supply— 75 for example, the series of air-heating flues I'', also arranged in the bottom of the furnace in rear of the fire-bridge. The air is driven by a jet of superheated steam issuing through a pipe, J'', inserted in the pipe or passage L, as 80 shown.

A channel, M, is arranged about midway in the height of the chamber C through its front wall, and another channel, N, is arranged at the bottom level, for purposes hereinafter explained, both being ordinarily kept closed by suitable doors or stoppers, m n.

Other features of the construction will be noticed in the description of the operation, which is as follows: The generator being first 90 heated in any convenient manner, and steam raised by a fire built in the bottom of the generator and upon the grate-bars O in the boiler-furnace, the body of fuel is gradually increased by accessions from above until the exit-throat D is practically filled with incandescent coals, the draft of the stack being supplied through the generator-openings M N. As soon as steam

is formed the blasts H and L are started and the openings M and N closed. Thus the gases evolved from the fresh charges of coal at the top are, by the aid of the upper blast, H, and 5 lower blast, L, caused to pass through the entire body of the incandescent and partly-spent coals in the exit-throat D, and heated and combined with the hot-air, and the water-gases, producing carbonic oxide and free hydrogen, 10 which issue in a highly-heated condition from the generator into the combustion-chamber E of the boiler-furnace.

In order to effect a thorough combustion of the gases thus produced, I provide a channel, 15 P, preferably narrow, extending horizontally across the top of the exit-throat, and a similar channel, R, extending across the bottom, both opening rearward into the combustion-chamber E. These channels are for the discharge 20 of heated air above and below the current of gases to aid their combustion. They may be supplied from heating-flues built in the side walls of the boiler-furnace, as indicated for the upper channel, P, by the dotted lines. The open- 25 ings P and R may be extended quite around the throat D, so as to surround the outgoing current of gases with a thin envelope of heated air. It will be readily seen that the passage of the current of gases through the throat will tend to 30 draw the air through the passages P R. For a similar purpose an air-discharge, S, is arranged across and in the bridge-wall, communicating with air-heating flues I³. The bridge-wall is inclined to the rear, and thus a similar effect is 35 produced by the currents of gases passing over it in drawing the air through the passage S. Thus the gases discharged from the generator, being intensely heated and in a state of pre-liminary combustion, are thoroughly ignited 40 by the accessions of heated air through the pas- 45 sages P, R, and S in the furnace under the boiler.

In case any stoppage occurs in the passage of the coal downward through the generator, 45 a poker may be inserted through the passages M and N, and by means of the latter the spent coal and ash may be shoved backward to the grates O and fall into the closed ash-pit beneath.

A supplemental air-passage, T, is provided, 50 connecting the air-channel P directly with the open air. By means of a suitable valve it may be opened, when necessary, for the purpose of admitting colder air beneath the boiler as a partial protection from too intense heat at that 55 point.

The throat D is constructed of refractory tiles or fire-brick, so as to admit a convenient renewal in case of injury from heat.

By this process a perfect combustion of the 60 carbon of solid fuels is effected, and the remaining ash is in the form of fine particles, commonly called "breeze," which are carried by the blasts into the combustion-chamber of the furnace and dropped through the grate into

the ash-pit. The degree of heat may be regu- 65 lated at will by graduating the force of the blasts, suitable valves being provided for the purpose in the steam-pipes J and J².

It will be obvious that my invention may be applied to any existing furnace with but little 70 alteration in the latter, and also that in iron-mills or other places where a number of furnaces are used a single producer may be used, and the gases conveyed by pipes to several furnaces at the same time or to a holder; but in 75 general it is found preferable to use a generator adapted to the capacity of the furnace and use the gas immediately on its production.

Having described my invention, I claim and 80 desire to secure by Letters Patent—

1. In a furnace, the combination of the retort-chamber having closed walls extending downward and terminating at the lower end in an exit-throat, arranged to discharge in an approximately horizontal direction into the 85 combustion-chamber of a boiler or other furnace, with top and bottom hot-air and steam-blast pipes or flues opening through the walls of the retort-chamber, and arranged to discharge highly-heated air and superheated steam 90 into the retort-chamber at the top and bottom portions of the fresh charge of coal, thereby forcing the gases evolved from the fresh charges through and over the incandescent coked portions at the exit-throat of the retort-chamber 95 and into the combustion-chamber of the boiler or other furnace.

2. In a furnace, the combination of the retort-chamber C, uniformly curved from the top to its bottom exit-throat, which opens into the 100 combustion-chamber E of a boiler or other furnace, with the top and bottom hot-air pipes, H and L, and top and bottom steam-pipes, J and J², all arranged to discharge highly-heated air and steam into the retort-chamber at its top 105 and bottom portions, to force the gases evolved at the top of the fresh charge of coal through the incandescent fuel in the exit-throat of the retort-chamber into the combustion-chamber of the boiler or other furnace, substantially as de- 110 scribed.

3. The combination, with the retort-chamber having the exit-throat D, opening into the combustion-chamber E of the boiler or other furnaces, of the top and bottom hot-air and steam 115 pipes discharging into the retort-chamber, and the channels P and R, extending across the top and bottom of the exit-throat D and opening into the combustion-chamber E, and both connected with hot-air flues, substantially as de- 120 scribed.

In testimony whereof I have hereunto set my hand in the presence of two subscribing witnesses.

CHARLES GEARING.
